UNITED STATES PATENT OFFICE.

FREDERICK W. TAYLOR, OF ST. JOHNSBURY, VERMONT, ASSIGNOR TO THE
E. & T. FAIRBANKS & COMPANY, OF SAME PLACE.

DESIGN FOR A POINTER.

SPECIFICATION forming part of Design No. 32,771, dated June 5, 1900.

Application filed May 1, 1900. Serial No. 15,143. Term of patent 14 years.

To all whom it may concern:

Be it known that I, FREDERICK W. TAYLOR, a citizen of the United States, residing at St. Johnsbury, in the county of Caledonia and 5 State of Vermont, have invented and produced a new and original Design for Pointers, of which the following is a specification, reference being had to the accompanying drawing, forming part thereof, in which the figure is a plan of a pointer, showing my new design.

As shown in the drawing, the leading or material feature of my design consists of a gooseneck extension A' at the outer end of 15 the pointer A, disposed or arranged as shown in the drawing. This gooseneck-finger is arranged so that its outer extremity will cooperate with an outer row of numerals, while

leaving an inner row exposed to view and with which the end a of the pointer co-oper- 20 ates.

It is apparent that this design is applicable to pointers wherever used.

Having thus described my invention, what I claim as new, and desire to secure by Letters 25 Patent, is—

The design for a pointer, as herein shown and described.

In testimony whereof I have signed my name to this specification in the presence of 30 two subscribing witnesses.

FREDERICK W. TAYLOR.

Witnesses:

JUNIUS H. BRAND,
WM. N. GILBERT.
